US00D772025S

(12) **United States Design Patent** (10) **Patent No.:** **US D772,025 S**
(45) **Date of Patent:** **** Nov. 22, 2016**

(54) **TORTILLA CHIP FUNNEL**

(71) Applicant: **Tyson Foods, Inc.**, Springdale, AR (US)

(72) Inventor: **Gregory Vernon Salzl**, Spokane, WA (US)

(73) Assignee: **Tyson Foods, Inc.**, Springdale, AR (US)

(**) Term: **14 Years**

(21) Appl. No.: **29/498,927**

(22) Filed: **Aug. 8, 2014**

(51) LOC (10) Cl. **07-99**

(52) U.S. Cl.

USPC **D7/700**

(58) **Field of Classification Search**

USPC .... D7/700, 354, 356, 357, 361, 368, 396.2, D7/667, 400, 409, 543, 523, 510, 512, 629, D7/668, 669, 691, 589, 412, 415; D9/436, D9/434, 435, 503, 536; D10/46.2; D14/208; D15/150, 152; D23/200; D24/121, 122, 123; D30/129, 132, 162 CPC A61F 5/4556; A61F 5/4553; A61F 5/455; A61F 5/451; A61F 5/44; A61F 5/453; B01D 23/28; B01D 23/00; B01D 23/005; B01D 23/10; B01D 23/20; B01D 29/00; B01D 29/0002; B01D 29/0093; B01D 29/0095; B01D 29/0097; B01D 29/085; B01D 29/11; B01D 29/112; B01D 29/114; B01D 29/117; B01D 29/13; B01D 29/31; B01D 29/115; B01D 29/118; B01D 29/15; B01D 29/23; B01D 29/33; B01D 29/35; B65B 39/00; B65B 39/04; B65B 39/001; B65B 39/06; B65B 39/12; B65B 39/14; F16N 31/00; B67C 2011/00; B67C 2011/02; B67C 2011/20; B67C 2011/30; B67C 2011/40; B67C 2011/022; B67C 2011/027
